UNITED STATES PATENT OFFICE.

WILLIAM PAGDEN PERRY, OF LEYTONSTONE, LONDON, ENGLAND.

APPARATUS FOR DISTILLING CARBONACEOUS MATERIAL.

1,341,517.

Specification of Letters Patent.

Patented May 25, 1920.

Application filed July 23, 1918. Serial No. 246,327.

To all whom it may concern:

Be it known that I, WILLIAM PAGDEN PERRY, a subject of the King of Great Britain, residing at Leytonstone, London, 5 England, have invented certain new and useful Improvements in Apparatus for Distilling Carbonaceous Material, of which the following is a specification.

This invention has reference to an improved construction of apparatus in which a continuous process for the separation of volatile products from solid carbonaceous material such as peat, shale, coal, wood or the like can be carried on and is of the type 10 in which distillation is effected by actual contact of hot gas with the material to be distilled.

Essential parts of my invention are; a single container or producer retort (which 20 constitutes in itself the retort containing the matter to be distilled and means for heating such matter), and above the CO zone a plurality of ring shaped areas, free from material next to or in the walls of 25 such container, having suitable outlets connected therewith for conducting away the vapors and gases, and in some cases also a tube or tubes positioned in the retort and provided with shielded openings along its 30 length for conducting some of the CO from the CO zone through the material at varying heights and thence into the vapor pipes thus assisting in the distillation.

The container may be constructed of any 35 suitable material such as iron, brick or reinforced concrete and may be lined with firebrick or other fireproof material and between the fireproof material and the wall in the lower part only or all the way up, I prefer 40 to provide a luting of sand, grit or similar material, and such container or producer retort is provided or constructed above the CO zone with a series of superposed spaces or areas formed in or attached to the wall 45 and completely around the same, the spaces or areas being so positioned or the wall being so constructed or provided that such spaces or areas are always left free from the material under treatment, such material 50 gradually falling from the top of the retort or container to the ash pit during combustion.

Connected with each space or area is one or more draw off pipes through which the 55 vapors or gases of distillation are drawn and by reason of the spaces or areas the

vapors or gases are freely drawn from all around and through the body of material lying within the compass of each ring space or areas thus effectually acting upon all the 60 material, and further a blockage of the outlet pipes by the material is obviated.

The dimensions and shape of the container may differ greatly with the nature of the material to be distilled and the rate 65 at which it is to be supplied with air or with air and steam or with air and gas and steam.

The container is designed for up draft combustion, the draft to be maintained in 70 any case by suction in the vapor pipes and which may be supplemented by pressure of air or steam or both under the grate, or open hearth or in any case under the material.

In order that the invention may be clearly understood and readily carried into effect two examples of the same will now be described with reference to the accompanying drawings, in which:—

Fig. 1 is a vertical section of a container or producer retort and apparatus connected therewith and in which the ring area or spaces are formed by ledges projecting from the wall of the retort.

Fig. 2 is a horizontal section of two containers or producer retorts forming part of a line battery of containers or producer retorts.

Fig. 3 is a vertical section of a container or producer retort and apparatus connected therewith and in which the ring areas or spaces are formed by the wall being formed in reversed stepped formation.

Fig. 4 is a similar view to Fig. 1 but showing a tube positioned in the retort to conduct CO from the CO zone to the material at different heights and thus assist in the distillation.

A is the wall of the container and B is the fireproof lining thereof and C the luting and D, D stoking holes.

The wall A in Fig. 1 is constructed on the inside with ledges or projections E all around and of the same diameter such ledges 105 E being in number and superposed, the top part being angled to cause the material resting on same to fall due to combustion and consequent reduction of the material below whereas in Fig. 3 the projections or 110 ledges E are so to speak inverted and of varying diameters, and in both cases as the

material falls it cannot enter the spaces or areas F below the ledges or projections thus leaving such spaces or areas F free.

At each of these spaces F are positioned 5 the draw off pipes G, G¹, G², G³, G⁴ so that by reason of the spaces or areas F always being kept clear the gas or vapor from the material in proximity to each space or area F is drawn freely therefrom and there 10 can be no blocking of such draw off pipes G. H is the CO₂ zone, I the CO zone, and J¹, J², J³ and J⁴ represent the distilling zones at progressive heights and temperatures.

The draw off pipes G are each provided 15 with a cover K at their ends which can be removed to clear the pipes G when required and to a branch L a suction blower or pump M is connected (drawn by any suitable power and gearing not shown) a branch 20 from the blower or pump M connecting to an outlet pipe P communicating with separate or a single condensing apparatus and separators for action in the manner well known, but each outlet G may be connected 25 by one pipe to one suction pump or blower communicating with one condensing apparatus and separators.

Q is the grate and R is the ash pit, the 30 openings S, S supplying air for combustion purposes. Under the grate Q I position a hooded pipe T leading from a steam supply and which I employ for supplying steam to the material for the evolution of ammonia and further if the fixed carbon in the char- 35 coal or coke (in the CO and CO₂ zones) is insufficient, for providing, by combustion, enough heat for the evolution of hot pro- 40 ducer gas and ammonia, I also affix a gas pipe U leading from a gas main and a gas pipe V leading from the condenser, so as to conduct uncondensed retorted gas or gas from any source to supplement the free car- 45 bon in the material.

The material is fed to each retort by a 50 screw conveyer W running along all the retorts of the battery or I may employ any suitable type of conveyer the material falling into each retort through a hopper X on to a valve Y and into the retort the valve 55 being closable when the retort is sufficiently full, and the ash pits R are provided with a conveyer Z for removal of the debris.

The peat or other carbonaceous material 60 is fed into the container by means of the screw conveyer W, the hopper X and the revolving feeding valve Y, the latter in any position preventing either gas escaping or air entering through the hopper X.

From the grate Q upward, to a distance 65 of several feet, the conditions obtaining in the material in the container are the counter- part of the interior of a generator of an ordinary gas producer. Above the grate the combustion zone D commences where mainly the combination of oxygen and car-

bon into CO₂ takes place, and the evolution of ammonia from the nitrogen in the material and the hydrogen in the steam and this section H extends as far upward as any free oxygen remains to be combined. Next 70 above this point the carbon dioxid, in contact with incandescent fuel, is converted into carbon monoxid. At the top of the CO zone I, at which point practically all the CO₂ has been converted into CO, the gas 75 can give up no more oxygen and it now has only heating and transporting effects, grad- ually, through J, J¹, J², J³, and J⁴ giving up its heat and lowering its temperature until part of it reaches the top of the ma- 80 terial being distilled at J⁴. The gas in pass- ing upward through the material, and heat- ing it, separates the volatile constituents and carries them along with it.

The gas and distillates are sucked through 85 outlets G⁴, G³, G², G¹ and G and gas on leaving the CO zone I is at a comparatively high temperature and the temperature steadily falls until the portion of gas which reaches the top of the container at J⁴ has 90 fallen to nearly the same temperature as the incoming material.

The material after entering the container having descended a short distance in zone 95 J⁴ is slightly raised in temperature by the ascending gas, thus causing the separation of the most volatile distillates which are now drawn into the nearest gas exit at G⁴. On descending lower the material is further raised in temperature by meeting hotter 100 gas which causes constituents which are less volatile to be separated and they find their way out by the next outlet G³. On further descent the material is heated still higher when the still less volatile constituents sepa- 105 rate and leave by the nearest outlet G². This is repeated step by step until finally, at a point just above the top of the CO zone I the least volatile of the distillates are sepa- 110 rated and leave by the lowest outlet G.

The material has now reached a condition similar to charcoal or coke and in this state enters the zone I. There part of it com- 115 bines with the rising CO₂ to become CO, while the remainder passes still lower into the zone H there to combine with rising oxygen to become CO₂, and the ammonia has been evolved the ash falls below the grate Q into the ash pit R where it is re- 120 moved by the conveyer Z.

I do not confine myself to the number of vapor rings that I have shown in illus- trations but in carrying out this invention I may employ any number of single rings at different heights.

According to the construction shown in Fig. 4 I employ a tube W¹ or tubes positioned in the retort and closed at the top or constructed arranged or provided with a hood X¹ for preventing entry of the mate- 125 130

rial into the tube W^1 . The bottom of the tube W^1 is open and positioned just above the CO zone and the tube W^1 is provided with shielded outlets Y^1 in its wall positioned 5 with the openings preferably about mid distance between each vapor outlet the tube W^1 running to any desired height in the retort.

The CO enters the tube W^1 at the base and passes upward and through the outlets 10 Y^1 into and through the material into the vapor pipes and away from the retort taking the volatile and other products with it. By this means the CO instead of being drawn completely through the whole mass 15 of material to the respective outlets is caused to permeate through the material in strata formation as well as passing through the whole body of material the tube W^1 acting as a by pass and insuring a better distribution of the CO through the retort. 20

What I do claim as my invention and desire to secure by Letters Patent, is:—

In a distilling apparatus, a vertical container having its inner walls so formed as 25 to provide a series of abutments at different elevations throughout said container, said abutments providing in combination with the walls of said container gas collect-

ing spaces, a grate positioned in said container adjacent the lower end thereof, a lining of refractory material on the inner walls of said container above said grate, the walls of said container being provided with openings above said grate adapted to serve as poke holes, means for removing the accumulated gases from said gas collecting spaces, means positioned below said grate for introducing gas and steam into the material to be treated, means to introduce the material into said container, 40 means to remove the residue of material from the container after the same has been treated, and means comprising a vertical tube having downwardly extending outlets positioned within said container 45 above the grate for introducing gases generated in the material adjacent said grate into the material under treatment at various levels.

In testimony whereof I have hereunto set 50 my hand in presence of two subscribing witnesses.

WILLIAM PAGDEN PERRY.
